UNITED STATES PATENT OFFICE.

GEORGE W. GRIGG, OF PORTLAND, OREGON.

WINDOW-SHADE CONTAINER.

Application filed July 8, 1920. Serial No. 394,638.

To all whom it may concern:

Be it known that I, GEORGE W. GRIGG, a citizen of the United States, residing at Portland, in the county of Multnomah, State 5 of Oregon, have invented a new and useful Window-Shade Container; and I do hereby declare the following to be a full, clear, and exact description of the invention, such as will enable others skilled in the art to 10 which it appertains to make and use the same.

The invention relates to window shade containers and has for its object to provide a device of this character, which will 15 encase a window shade and its brackets so that curtains, for—instance lace curtains will not become entangled with the shade and its bracket.

A further object is to provide a window 20 shade attachment casing which casing has its ends formed from sheet metal and its body portion formed from wood, the bottom of said casing being provided with an elongated opening through which the shade feeds when being pulled down.

With the above and other objects in view the invention resides in the combination and arrangement of parts as hereinafter set forth, shown in the drawings, described 25 and claimed, it being understood that changes in the precise embodiment of the invention may be made within the scope of what is claimed without departing from the spirit of the invention.

In the drawings:—

Figure 1 is a front elevation of the casing showing the same attached to a window frame and encasing a window shade.

Figure 2 is a bottom plan view of the 40 shade casing.

Figure 3 is a longitudinal sectional view taken on line 3—3 of Figure 1 looking in the direction of the arrows.

Figure 4 is an enlarged end view of the 45 casing.

Referring to the drawings, the numeral 1 designates a conventional form of window frame and 2 a shade, which shade is mounted in the brackets 3, which are secured to the 50 window frame. Brackets 3 are of the con-

ventional form. The shade casing 4 comprises the top, front and bottom strips 5, 6 and 7, which strips are preferably made of wood, and the bottom and bottom strip 5 and 7 are secured to the end metallic members 8 by means of angles 9, which angles are secured to the ends 8 and to the strips by means of screws 10. It will be seen that a rigid case is provided formed from metal and wood, which will entirely encase the 60 shade.

The strip 7 is narrower than the strip 5 thereby forming an elongated opening 11 through which the shade 2 will feed. For additionally holding the ends 8 and bracing 65 the same, adjustable bolts 12 are provided and are carried by the ends of the front strip 6, the threaded portions of which bolts engage notches 13 of the end plates 8, said adjustable bolts being adjustable by means 70 of elongated apertures and screws 14.

From the above it will be seen that a curtain shade casing is provided, which combines the use of wood and metal, thereby forming a rigid structure and it will also 75 be seen that a shade casing is provided which may be easily and quickly placed over the shade. The great difficulty with shades where they are not encased has been the fact, that where curtains are used, the curtains 80 become entangled in the shade and its brackets and consequently are damaged. By providing a casing of the character described, this difficulty is obviated.

It will also be seen that by forming the 85 casing of the two materials that is wood and metal the casing may be cheaply constructed and at the same time the weight may be reduced to a minimum without sacrificing strength.

The invention having been set forth what is claimed as new and useful is:—

A shade casing comprising an elongated rectangular shaped casing adapted to be disposed over a shade, the front side of said 95 casing being removable, the ends of the casing extending beyond the front side thereof and provided with notches, said front side of the casing having threaded bolts longitudinally adjustable thereon adjacent its 100

ends, said bolts being received in said notches and nuts threaded on said threaded bolts and engaging the outer faces of the ends of said casing, the upper and lower sides of the 5 casing being also removable, thereby allowing access to the curtain from above or below the casing.

In testimony whereof I have signed my name to this specification in the presence of two subscribing witnesses.

GEORGE W. GRIGG.
